7 Claims

ABSTRACT OF THE DISCLOSURE

An apparatus is here taught for increasing the range and mobility of swimmers. The apparatus includes a hull held in spaced relationship from the swimmer's breast. The hull journals a shaft which has a propeller operatively mounted thereto. Two spools are arranged about the shaft and are each provided with clutches whereby each drives the shaft when rotating thereabout in a like positively defined sense and whereby they slide freely about the shaft in a negative sense. A pair of flexible elements are each wrapped about one of the spools in an opposite sense and each element is connected to one of the feet of the swimmer whereby when the swimmer alternately extends and retracts his feet in a normal stepping motion, he exerts positive pulls alternately on the spools. These positive pulls integrate for continuous driving of the propeller.

BACKGROUND

Many devices for use by swimmers are driven by motors or batteries. With such craft the swimmer rides—he does not swim, so there is a sacrifice of exercise. In U.S. Patent 3,349,746 this inventor disclosed a prior version of a craft to propel a swimmer and which adapted a natural stepping action of the swimmer's legs for continuously turning a propeller. The present invention is a simple, inexpensive and advanced apparatus of the same kind.

SUMMARY

As in this inventor's prior version of an apparatus for swimmers, a rod is connectable between the body of the swimmer and a hull for positioning the hull in spaced relationship from the swimmer's breast. The hull journals a shaft which has a propeller operatively mounted thereon. In the present apparatus, two spools are arranged about the shaft and are each provided with clutches whereby each drives the shaft when rotating thereabout in a like positively defined sense and whereby each spool rotates freely about the shaft in a negative sense. A pair of flexible elements are each wrapped about one of the spools in senses opposite each to the other and each element is connected to one of the feet of the swimmer whereby when the swimmer alternatively extends and retracts his feet in a normal stepping motion, he exerts alternate positive pulls on the spools which integrate for continuous driving of the propeller.

The primary objective of this invention is to increase the range and mobility of a swimmer.

A further objective is to adapt more effectively a natural stepping action of the swimmer's feet for continuously turning a propeller to move the swimmer.

A further objective is to have the swimmer participate physically in his movement. Speed and maneuverability depend up on the swimmer's strength and coordination, so this apparatus lends itself to athletic competition. It will be seen readily that this apparatus adds scope to water polo and other team sports because courts can be enlarged. The apparatus can be used either on or below the surface, so water games can include self-contained underwater breathing apparatus.

A further objective is to provide an apparatus to in-

2

crease the range and mobility of a frogman for military purposes, because this apparatus emits no gases. It is intended to reduce the frogman's liability of being detected.

5 A further objective is to present a more simple and inexpensive apparatus which needs neither fuel nor batteries, needs practically no maintenance and is otherwise well suited to its intended task.

DRAWINGS

10 The foregoing and other objectives will be seen more fully from the accompanying drawings wherein:

FIGURE I is a sketch illustrating a swimmer using the apparatus of this invention.

15 FIGURE II is a front elevation of the apparatus showing among other things the sense of rotation of the propeller.

FIGURE III is a partial side elevation of the apparatus as seen from the swimmer's left.

20 FIGURE IV is a fragmented plan view in section taken along line IV—IV of FIGURE II and with the handles omitted.

FIGURE V is a fragmented detail section of the shaft with the propeller and spool mounted thereon.

25 FIGURE VI is a fragmented detail section taken along both lines VI—VI of FIGURE IV and showing the clutch arrangement between the spools and the shaft.

PREFERRED EMBODIMENT

30 As best seen in FIGURE I this apparatus comprises a hull generally designated 1 which is connected to a swimmer who is immersed prone in water. To orient the swimmer relative the hull, rod 2 is fixed to hull 1 and is connected by means of ball and socket joint 3 to the swimmer's harness which is shown as band 4 encircling the swimmer's waist. Harness of this kind are described more fully in U.S. Patent 3,349,746. As pointed out in that patent, the swimmer may use apparel which includes either air pockets for buoyancy or weights for maintaining the swimmer below the surface of the water. Also such devices may be included in the hull itself.

An important aspect of the present invention is to adapt a natural stepping action of the swimmer's feet to turn propeller 6 for moving the swimmer. As best seen from FIGURES I and IV, first 7 and second 8 flexible elements are connected over pulley 9 to the swimmer's left foot. First 7 and second 8 flexible elements are also connected over pulley 11 to the swimmer's right foot. For convenience, directions and senses of rotation will be taken from the swimmer's point of view. By means of alternating reciprocal movements of the swimmer's feet (as in a normal walking step) the ends of the first 7 and second 8 elements connected to the swimmer's left foot and those ends connected to the swimmer's right foot are pulled and relaxed in turn. First flexible element 7 penetrates hull 1 via passage 12 and over guide bosses 13 and wraps about first spool 14 so that on extending the swimmer's left foot to pull first element 7, first spool 14 is turned in a clockwise sense. As seen from FIGURE VI, circular elements 16 of the corresponding clutch are thereby pinched between shaft 17 and first spool 14 whereby shaft 17 is turned and propeller 6 is driven in a clockwise sense. On the same extension of the swimmer's left foot second 8 flexible element which penetrates hull 1 via passage 18 and over guide bosses 19 wraps about second spool 21. As seen from FIGURE VI, circular elements 16 of the corresponding clutch are thereby moved into the deep end 21 of recesses 23 where they clear shaft 17 and second spool 21 slides freely in a counter-clockwise sense over the clockwise rotating shaft to wind up second element 8.

Conversely second element 8 is similarly organized relative the swimmer's right foot so that on extending the swimmer's right foot to pull second element 8, second spool 21 is turned in a clockwise sense. As seen from FIGURE VI, circular elements 16 of the corresponding clutch are thereby pinched between shaft 17 and spool 21 whereby the shaft is turned and propeller 6 is driven in a clockwise sense. Also on the same extension of the swimmer's right foot, first flexible element 7 wraps about first rotating spool 14 to be in a position for the next extension of the swimmer's left foot.

As best seen in FIGURES III and IV, to prevent flexible elements 7 and 8 from falling off spools 14 and 21, rollers 27 are provided.

It will be apparent to those skilled in the art here involved that wide deviations may be made from the preferred embodiment set forth above without departing from the scope of invention contemplated in the following claims. By way of example the circular elements 16 in the clutches could be rods instead of ball-bearing. Also, bushings 24 of tetrafluoroethylene and washers 26 of the same material can be employed to reduce friction.

What is claimed is:

1. An apparatus for moving a swimmer and comprising
a hull having a shaft journaled thereto and a propeller
mounted on the shaft,
25 rigid means connectable between the body of the
swimmer and the hull for positioning the hull in
spaced relationship from the swimmer,
a first and a second spool each arranged about the
shaft and each having clutch means whereby the
spool drives the shaft when rotating in a like posi-
tive sense and whereby the spool rotates freely in
the opposite sense,
a flexible first element wrapped about the first spool
and connected to both feet of the swimmer where-
by when the swimmer extends his left foot in a na-
tural stepping motion he exerts a pull on the first ele-
ment rotating the first spool in its positive sense,
a second flexible element wrapped about the second
spool in a sense opposite to that of the first element
about the first spool and connected to both feet of
the swimmer whereby when the swimmer extends his
right foot in a natural stepping motion he exerts
a pull on the second element turning the second spool
in its positive rotational sense,
40 the first element arranged to rewind on the first spool

as the right foot extends and the second element ar-
ranged to rewind on the second spool as the left foot
extends,
the first and second flexible elements comprising a con-
tinuous element,
stirrups connectable to each of the feet of the swimmer,
each of the stirrups having a pulley rotatably mounted
thereon,
the first and second flexible elements connectable to the
swimmer's feet over the pulleys.

2. The apparatus of claim 1 with
one of the spools mounted fore and one aft of the
propeller,
the hull embracing the spools the propeller.
3. The apparatus of claim 2 wherein
the shaft is cylindrical,
each of the spools has a generally cylindrical inside
wall,
each of the clutch means comprising at least one recess
provided in the inside wall of the spool and gradu-
ally increasing in depth toward the positive sense,
a circular element in the recess and having a diameter
less than the maximum depth of the recess whereby
on turning the spool in its negative sense the circu-
lar element moves into the bottom of the recess so
that the spool slips over the shaft and whereby on
turning the spool in the positive sense the circular
element is pinched between the spool and the shaft
so that the shaft is driven.

- 30 4. The apparatus of claim 3 with each of the clutch
means including at least three of the reasons and circular
element combinations.
5. The apparatus of claim 4 with ball bearings as the
circular elements.
- 35 6. The apparatus of claim 5 and the hull provided with
bearings lined with tetrafluoroethylene for journaling the
shaft.
7. The apparatus of claim 6 with the hull defining pas-
sages and guide bosses to receive the flexible elements
40 therein.
